BY
Fred C. Fraenzel,
ATTORNEY

UNITED STATES PATENT OFFICE.

HENRY ILL, OF NEWARK, NEW JERSEY.

DESIGN FOR A CASTER-PIN.

SPECIFICATION forming part of Design No. 25,522, dated May 19, 1896.

Application filed December 18, 1895. Serial No. 572,602. Term of patent 14 years.

To all whom it may concern:

Be it known that I, HENRY ILL, a citizen of the United States, residing at Newark, in the county of Essex and State of New Jersey, have 5 invented a certain new and useful Design for Caster-Pins; and I hereby declare the following to be a full, clear, and exact description of the same, such as will enable others skilled in the art to which it appertains to make and 10 use the same, reference being had to the accompanying drawings, which form part of this specification.

My invention relates to a novel design for 15 caster-pins; and it consists in the novel configuration shown.

The design is clearly illustrated in the accompanying drawings, in which—

Figure 1 is a side elevation of my novel design of caster-pin; and Fig. 2 is a cross-section of the same, taken on line .x in said Fig. 1.

The leading feature of my novel design is a caster-pin having a plain cylindrical portion a' , which terminates in an oval head a^2 , surrounded by a beaded or beveled edge a^3 , 25 as shown. Above said plain cylindrical portion of the pin is a portion a of a slightly-increased diameter over the diameter of the said plain cylindrical portion a' , said enlarged portion being ornamented with an especial configuration having a rope-like appearance. Said enlarged portion a is bounded at its lower 30 part with the angularly-disposed parts a^4 and at its upper part with the angularly-disposed parts a^5 , said parts a^4 and a^5 forming zigzag edges, which bound said enlarged portion a 35 at the top and bottom, as shown. Connecting the several points of said zigzag edges a^4 and a^5 are a number of longitudinal ridges

a^6 and depressions a^7 , which are helical curves and form half-turns to produce the rope-like 40 ornamentation of the said cylindrical surface a and also produce a many-pointed star-shaped figure in cross-section, as illustrated in Fig. 2. Said helical ridges and depressions are closely disposed upon said enlarged surface a of the caster-pin and are bounded at the top by the zigzag edge a^8 , above which the remaining portion of the caster-pin is of a plain cylindrical shape a^9 of a slightly smaller 45 diameter than the diameter of the enlarged portion a . Said plain cylindrical portion a^9 is bounded by a slightly curved or rounded edge a^{10} , as clearly represented in Fig. 1.

The essential and novel feature of the design for a caster-pin is the plain cylindrical 55 portion a' at the bottom of the pin and the plain cylindrical portion a^9 at the top of the pin with a slightly-enlarged portion a disposed between them, having many longitudinal and helical ridges and depressions forming 60 a rope-like ornamentation on said enlarged portion a , producing a many-pointed star-shaped figure when viewed from the top, and said portion a being bounded at the top and bottom by zigzag edges, as illustrated. 65

Having thus described my invention, what I claim is—

The design for a caster-pin, substantially as herein shown and described.

In testimony that I claim the invention set 70 forth above I have hereunto set my hand this 17th day of December, 1895.

HENRY ILL.
